UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,584.

Specification of Letters Patent. Patented Apr. 15, 1919.

Application filed August 23, 1917. Serial No. 187,803.

To all whom it may concern:

Be it known that I, MOSES F. CARR, a citizen of the United States, and a resident of Newton, in county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in fasteners, and more particularly, though not exclusively, to improvements in snap fasteners in which separation of two engaging elements can be effected by tipping movement of one of said elements in one direction only.

20. In the drawings:

Figure 1 is an elevation of a preferred form of fastener constituting one embodiment of my invention;

25. Fig. 2 is a section on the line 2—2 of Fig. 1;

Fig. 3 is a section on the line 3—3 of Fig. 2.

It is among the objects of this invention to provide a snap fastener of cheapened construction in which the number of parts is reduced to a minimum. It is the usual construction in snap fasteners to provide a socket having a front plate and a back plate for attachment thereto, a spring being interposed between the front and back plates. It is among the objects of this invention to dispense with the back plate while leaving unimpaired the efficiency of the fastener and the positioning of the spring.

40. Referring to the drawings, I have shown a stud 4 having a head 5 adapted to pass between jaws 6 and 7 held in a socket. In the preferred form of my invention the socket comprises a single stamped plate 8 having flanges 9 around the edges thereof and having portions of the front thereof died inwardly to provide spring positioning means 10 and 11, said spring positioning means performing the function normally

45. performed by the intermediate plate of the usual commercial socket. The socket is preferably formed so that the spring jaws 6 and 7 may be made from a single piece of wire and may be assembled with the socket by

55. pressing the spring into the front of the

socket from one end, the jaws 6 and 7 passing in front of the spring-retaining elements 10 and 11.

The stud 4 may be of any suitable type, but preferably coöperates with the jaws 6 and 7 to prevent rectilinear separation of the stud and socket and to permit separation of stud and socket by tipping movement in one direction only.

While I have shown and described one embodiment of my invention, it is obvious that changes involving omission, alteration, substitution and reversal of parts, and even changes in the mode of operation, may be made without departing from the scope of my invention, which is best defined in the following claims.

Claims:

1. A socket for separable fasteners comprising a single plate having portions projecting in a plurality of planes to receive and support on opposite sides jaw means, said portions permitting insertion or removal of said jaw means subsequent to completing the formation of said plate. 75

2. A stud and socket fastener comprising, in combination, a stud providing a head and a neck, a socket providing two resilient jaws and a casing for said resilient jaws having one side thereof partially projecting inwardly to provide a support for said resilient jaws on the inward side thereof. 85

3. A socket for separable fasteners recessed to receive an inner resilient element providing two jaws, said socket providing recessed portions projecting inwardly from the face thereof, said socket permitting the assembly of said resilient element therewith while supporting opposite sides of said jaws. 90

4. A socket for separable fasteners comprising a pair of jaws bent from a single wire, and a casing for said jaws providing a supporting surface in the plane of said jaws forwardly thereof and a supporting surface in the plane of said jaws rearwardly thereof, the last named supporting surface being formed by a strip projecting inwardly from the first named supporting surface. 100

5. A socket for separable fasteners comprising a strip of wire bent to provide two inwardly projecting jaws, and a casing formed of a single sheet of metal formed to provide a supporting surface in front of said jaws and a plurality of supporting strips rearwardly of said jaws. 105 110

6. A socket for separable fasteners having resilient jaw means, and a casing formed of a single strip of metal, said casing and said jaw means being interwoven each with the other.
7. A socket for separable fasteners comprising a resilient jaw 7, and a casing 8 providing strips 12 and 13 forward of said jaw and strips 10 and 11 rearwardly of said jaw.
8. A socket for separable fasteners com-

prising resilient jaws 6, 7, and a casing 8 providing strips 12, 13 forward of said jaws and a strip 10 rearwardly of said jaws.

9. A socket for separable fasteners comprising resilient jaws 6, 7, and a casing 8 ¹⁵ providing strips 12, 13 forward of said jaws and a strip 11 rearwardly of said jaws.

In testimony whereof I have signed my name to this specification,

MOSES F. CARR.
